THERMOSTATIC SWITCH

Frederick Louis Hollister, Richmond, England

Application August 12, 1946, Serial No. 689,901
In Great Britain August 13, 1945

13 Claims. (Cl. 200—137)

1

The present invention comprises improvements in or relating to electric current switches and relates more particularly to such switches in which a rapid make or break of a current circuit is desired with only a small relative movement between the switch contacts. The latter feature is particularly desired in switches for the operation of which mechanical movements of only small extent are available, as for example in thermostat switches for controlling the supply of electric current to heating or refrigerating apparatus in which it is desired to maintain a substantially uniform temperature.

It is an object of the invention to provide a switch of the nature first described above which is satisfactory in operation and compact in structure.

According to the invention an electric current switch comprises a lever carrying a movable switch contact and a magnetic armature for effecting operation of the lever, and spring means to effect a reverse operation of the lever mounted to afford one part to be subject to an operating force and a second part to transmit an opposite resilient pressure on an arm of the lever.

According to the invention also an electric current switch, for example, a switch as described in the last preceding paragraph, comprises a lever which carries a movable switch contact and a magnetic armature for effecting operation of the lever and which is of channel section, and spring means to effect a reverse operation of the lever housed within the channel afforded thereby.

Preferably an electric current switch constructed in accordance with the invention comprises a magnetic keeper mounted to afford a supplementary shunt path for magnetic flux for spark quenching on separation of the contacts.

According to one constructional example of the invention the lever has a pivotal mounting serving also to support a spring having one arm to be subject to an operating force and a second arm formed with a return bowed portion secured to an arm of the lever.

In order that the invention may be more clearly understood a preferred constructional example will be described with reference to the accompanying drawings in which:

Figure 1 is a side elevation, partly in section, of a switch for effecting thermostatic control of electrical heating apparatus.

Figure 2 is a top plan view of the switch shown in Figure 1 with the outer cover removed.

Figure 3 is an end elevation, as seen from the right, of the switch shown in Figure 2.

2

Figure 4 is a section, as seen in the direction of the arrows, on the line 4—4 of Figure 2, and

Figure 5 is a section on an enlarged scale, as seen in the direction of the arrows, on the line 5—5 of Figure 2.

Like reference numerals are employed to denote like parts in the various figures of the drawings.

The switch shown in the drawings, as will be seen more particularly from the side elevation in Figure 1, has attached thereto a temperature responsive device for securing automatic operation of the switch. This device comprises a brass tube 10 secured to the base plate 11 and rigidly secured internally of the brass tube at its lower end by brazing, solder or the like 12 is an invar bar 13 having an upper end, seen more clearly in Figures 3 to 5, projecting through an aperture in the base plate 11 free from contact with the latter. The rod type temperature sensitive element shown is conveniently enclosed in a cylindrical casing 14 secured by the set screw 15 with the interposition of an insulating washer 16 between the base plate 11 and casing 14. The thermosensitive element and casing are intended to be immersed, for example in a hot water storage tank, screw-thread 17 being employed to effect a suitable mounting on the wall of the tank so that the actual switch described hereinafter is located externally and closely adjacent the wall of the tank.

The base plate 11 is conveniently of brass and has a terminal 18 for an electrical earth connection secured to it. A pair of screwthreaded pillars 19 are mounted in the base plate and surrounded at their base by brass distance pieces 20 and annular insulators 21 of any preferred insulating material. The insulators 21 are surmounted by a brass bracket 22 affording a supporting cradle between the pillars but offset laterally from them as seen in Figure 1. The bracket 22 is again surmounted by perforated arms of a permanent magnet 23, further annular insulators 24, a brass cross member 25 which is laterally offset from the pillars 19 in a direction

opposite to the offset supporting cradle 22, annular insulators 26 and screwthreaded brass securing nuts 27 of disc form having slots or grooves 28 (Figure 2) for engagement by a suitable tool for tightening. The switch mechanism is normally enclosed by a rectangular cover or box 29 conveniently built up from plates of synthetic plastic material or produced as an integrally formed moulding. The cover 29 (Figure 1) is perforated to receive the ends of the pillars 19 and is secured in position by nuts 30 screw-

threaded on the pillars. The cover 29 is dimensioned to fit on the base plate 11 at its free edges while the inner surface of the top of the cover is in contact with the retaining discs 27. The cover 29 is also secured by a pair of screws 130 which take into screwthreaded apertures respectively provided in a lug 31 depending from the cross member 25 and a bracket 32 upstanding from a fixed insulating support 33 secured to the base plate 11 and located so that the cover 29 fits snugly between the earthing terminal connection 18 and insulating support 33.

The screws 130 afford or are secured to a pair of current supply lead connections, the cross member 25 having secured to it a suitably coated copper switch contact 34 having a screwthreaded shank 35 secured by the nut 36. The contact 34 is located substantially between the poles of the horse-shoe magnet 23 which are shaped to form a partial shroud for the contact, while a shaped soft iron keeper 37 is also secured to the cross member 25 to effect a more complete magnetic shrouding of the switch contacts. The similar co-operating switch contact 38 is superimposed on an armature 39 subject to the action of the magnet and carried with the contact 38 at one end of a channel section lever 40 pivotally carried by a pair of pivots 41 mounted in the supporting cradle 22, as will be seen more clearly from Figures 3 and 5, and passing through the side flanges of the lever 40. A further smaller short channel section member 42 is located within the channel section of the lever 40 and also pivotally mounted on the pivots 41. A pair of insulating plates 43 disposed in the channel member 42 embrace a flat spring strip 44 one end of which is secured to a lateral base extension 45 (Figure 4) of the upstanding bracket 32 on the insulating support 33. The spring strip passes substantially through the axis of the pivots 41 and is formed at its other end with a return bowed portion 46 secured to the underside of the arm of the lever 40 remote from the switch contacts 34 and 38, the latter being conveniently enclosed in a shrouding mica tube 47. The spring strip acts as a current conductor from the lever 40 and contact 38 to one terminal connection 30. The mica tube 47 enables the magnet poles and keeper 37 to be placed closely together so that an effective shunt or diverter path for magnetic flux is provided when the switch contacts are separated.

The switch contacts are normally held in engagement by the action of attraction of the magnet 23 on armature 39 but rocking of the lever 40 to break this engagement is effected by pressure on the extended arm of the spring strip 44. In the present construction of switch for thermostatic control of electrical heating apparatus the movable member 13 of the temperature sensitive device is secured to a frame piece 48 carrying a depending rod 49 passing through an aperture in the lever 40 to bear against the upper insulating plate 43 in a position displaced from the axis of the pivots 41. Expansion of the brass tube 10 causes pressure by the rod 49 on the spring 44 to rock the lever 40 and separate the contacts 34 and 38 to interrupt the supply of heating current. The latter will normally be an alternating current mains supply and the keeper 37 affords a supplementary shunt or diversion path for magnetic flux when the switch contacts and the armature and magnet poles are separated. Such a shunt path aids in spark quenching by acting as a magnetic blow out. In addition the speed of the make and break is arranged to be such as

10 to be complete within a current half cycle period to prevent re-establishment of an arc after the current surge reaches a zero value. Uniform operation of the switch is secured due to absence of serious distortion in the form of spring which is adopted. Movements to effect operation of the switch and the separation of the contacts are in all cases very small, and to limit the travel of the lever 40 the flanges are shaped at its forward or contact end to act as a limiting stop by engagement with the base extension 45 of the bracket 32.

15 The construction which has been described may have parts formed or die cast from other metal, such as aluminium, or may have many parts formed from moulded plastic material which also gives satisfactory insulation. Modification of the construction provided in accordance with the invention is also possible, for example by the inclusion of a dash-pot or like device for damping the movement of the switch to secure a time lag in its operation under the influence of the magnet. A hand or finger operated lever may also be provided either in addition or in place of the 20 temperature sensitive control, the said lever operating a suitable cam or intermediate lever for exerting an operating pressure on the spring strip. Any form of remote control of the operation of the switch may be adapted and control of the 25 operation of the switch may be effected by means other than a temperature sensitive device such as by fluid pressure, e. g. with the use of compressed air or a Bourdon tube device, or by a water level control or electromagnetic control.

30 In the specific example of thermostatic control switch described above, it is found convenient for the control of electrically operated refrigerators to arrange for a temperature sensitive device to exert an upward push on the spring element 44 on that side of the pivots 41 remote from the 35 switch contacts to secure the opening of the latter.

35 Adjustment of the temperature of operation of the construction of thermostat switch which is shown in the drawings is effected by adjustment 43 of the rod 49 which is carried by the screw 51 having a slot for engagement by an adjusting tool. The latter screw is carried in an internally screwthreaded collar having a head 50 and secured in the bridge or stirrup piece 48. If desired a rotatable part may be carried externally of the casing 29 and secured on an extension of the screw 51, so that the said rotatable part may be adjusted to a position giving a desired temperature control, by adjustment of an indicating 50 mark on the rotatable part to an appropriate position on a temperature scale inscribed on the casing 29.

40 In the use of the thermostat switch which has been described for effecting a control of the operation of an electric cooker or oven, the device shown in Figure 1 is conveniently mounted at a forward upper corner of the oven. The terminal connections as well as the earth lead are then preferably carried by the base member 11 and the casing 29 carried on the base 11 to be rotatable relatively thereto. The casing 29 is then of cylindrical form enclosing the switch mechanism and has a knurled periphery projecting through a suitable aperture in the front 45 casing of the oven for manipulation in accordance with actual temperature indications inscribed on the cover or on a drum or ring rotatable therewith and visible through a second aperture in the front casing of the oven. The 55 casing 29 is then secured to a screw, such as

screw 51 but having a coarser thread than the latter, serving to adjust the position of the switch operating rod 49.

I claim:

1. An electric switch of the character described comprising a stationary contact, supporting means for said stationary contact, a movable contact, a channel lever carrying said contact, a support pivotally carrying said lever, a magnetic armature for effecting operation of said lever, magnetic means adjacent said contacts to afford a supplementary shunt path for magnetic flux for spark quenching on separation of said contacts, spring means for actuating said lever, and a pivoted insulated cradle support for said spring, said pivoted insulated cradle support being housed together with said lever within the channel confines thereof.

2. An electric switch as claimed in claim 1 characterized by the fact that a terminal connection is provided to which one arm of said spring is secured.

3. An electric switch of the character described comprising a base plate, upstanding pillars therefrom, a stationary contact, a cross support carrying said stationary contact intermediate said upstanding pillars and carried thereby, a movable contact, a channel lever carrying said movable contact, a support pivotally carrying said lever, a magnetic armature for effecting operation of said lever, magnetic means adjacent said contacts to afford a supplementary shunt path for magnetic flux for spark quenching on separation of said contacts, spring means for actuating said lever, and a pivoted insulated cradle support between said upstanding pillars for said spring means, said pivoted insulated cradle support being housed together with said lever within the channel confines thereof.

4. An electric switch as claimed in claim 3 characterized by the fact that said cross member carries a magnetic keeper for said magnetic means carried by said upstanding pillars.

5. An electric switch of the character described comprising a stationary contact, supporting means for said stationary contact, a movable contact, a channel lever carrying said contact and having an opening therethrough, a support pivotally carrying said lever, a magnetic armature for effecting operation of said lever, magnetic means adjacent said contacts to afford a supplementary shunt path for magnetic flux for spark quenching on separation of said contacts, spring means for actuating said lever, a pivoted insulated cradle support for said spring, said pivoted insulated cradle support being housed together with said lever within the channel confines thereof, and a stirrup surrounding said lever and spring means for connection to a temperature sensitive element, said stirrup having an abutment to engage a portion of said spring means at a point free from contact with said lever by passing through the opening thereof.

6. An electric switch of the character described comprising a stationary contact, supporting means for said stationary contact, a movable contact, a magnetic armature, a lever carrying said movable contact and said magnetic armature, a support pivotally carrying said lever, magnetic means adjacent said contacts to afford a supple-

mental shunt path for magnetic flux for spark quenching on separation of said contacts, spring means for actuating said lever, and a pivoted insulated cradle support for said spring means.

5 7. An electric switch as claimed in claim 6 characterized by the fact that said magnetic means is a permanent magnet arranged with said stationary contact to co-operate with said magnetic armature carried by said lever to effect 10 operation of said lever in one direction.

8. An electric switch as claimed in claim 6 wherein said spring means is mounted to be subject to and to transmit an operating force to actuate said lever and said movable contact in opposition to said magnetic means.

15 9. An electric switch as claimed in claim 6 characterized by the fact that said spring means comprises a resilient leaf extending between a fixed anchorage and said pivot adapted to be rocked by movement of said leaf.

20 10. An electric switch of the character described comprising a stationary contact, supporting means for said stationary contact, a movable contact, a magnetic armature, a channel lever carrying said movable contact and said magnetic armature, an insulated cradle pivot support for carrying said channel lever, and a leaf spring one 25 end of which is extended beyond said pivot and secured to said lever and the other end of which is secured to said support means, said leaf spring being pivoted coaxially with said lever and housed within the channel confines of said channel lever.

25 11. An electric switch of the character described comprising a stationary contact, supporting means for said stationary contact, a movable contact, a magnetic armature, a channel lever carrying said movable contact and said magnetic armature, a pivot support for carrying said lever, an insulated cradle carrying said pivot support, 30 and a leaf spring connected between said pivot and said contact carrying lever to transmit an opposite movement to that of said leaf spring to one end of said lever to actuate said lever and said switch contacts.

35 12. An electric switch as claimed in claim 11 wherein said leaf spring and said channel lever will coaxially pivot, said leaf spring being within the confines of the walls of said channel lever.

40 13. An electric switch as claimed in claim 11 characterized by the fact that said spring leaf extends beyond said pivot to afford a return radius secured to said channel lever.
